United States Patent

Des. 240,583
Patented July 20, 1976

240,583

STAND FOR POTTED PLANTS AND THE LIKE

Michael Bohomoletz, R.D. 3, Box 312, Perrineville Road,
Robbinsville, N.J. 08691

Filed June 11, 1975, Ser. No. 586,098

Term of patent 14 years

Int. Cl. D6—04

U.S. Cl. D6—183

Fig. 2.Fig. 3.

FIG. 1 is an enlarged perspective view of a stand for potted plants and the like showing my new design;

FIG. 2 is a front elevational view, the rear being a mirror image; and

FIG. 3 is a bottom plan view.

I claim:

The ornamental design for a stand for potted plants and the like, as shown and described.
